(57) **CLAIM**

The ornamental design for a freezer tray as shown and described.

DESCRIPTION

FIG. 1 is a top perspective view of a freezer tray, showing my new design;

FIG. 2 is another top perspective view in another angle thereof;

FIG. 3 is a bottom perspective view thereof;

FIG. 4 is a front elevational view thereof, the rear elevational view, left elevational view and right elevational view are identical;

FIG. 5 is a top plan view thereof;

FIG. 6 is a bottom plan view thereof;

FIG. 7 is a partial enlarged view of FIG. 1;

FIG. 8 is a partial enlarged view of FIG. 2;

FIG. 9 is a partial enlarged view of FIG. 5;

FIG. 10 is a partial enlarged view of FIG. 5; and,

FIG. 11 is a cross-sectional view taken through line 11-11 of FIG. 5 thereof.

(Continued)

7

The broken lines in the figures are for the purposes of illustrating portions of the freezer tray, which form no part of the claimed design.
